UNITED STATES PATENT OFFICE.

AUGUST JOSEPH KOLLMAN, OF NEW YORK, N. Y.

DESIGN FOR A LAMP MOUNTING.

Application filed January 30, 1926. Serial No. 16,330. Term of patent 7 years.

To all whom it may concern:

Be it known that I, AUGUST J. KOLLMAN, a citizen of the United States, and a resident of the city of New York, borough of Manhattan, in the county of New York and State of New York, have invented a new, original, and ornamental Design for Lamp Mountings, of which the following is a specification.

Reference is to be had to the accompanying drawing in which the figure is a perspective view of a lamp mounting showing my new design.

What I claim is:

The ornamental design for a lamp mounting, substantially as shown.

AUGUST JOSEPH KOLLMAN.
